ELECTRICAL SYSTEM FOR COMPENSATING FOR LINE VOLTAGE VARIATIONS

Alexander Kusko, Newton Center, Mass.

Application May 14, 1954, Serial No. 429,731

8 Claims. (Cl. 323—66)

This invention relates to systems for compensating for variations in line voltage and other factors in an alternating current supply system and particularly to an arrangement for controlling a resonant circuit or static regulator in the system.

It is desirable in certain load circuits, such as lighting circuits, to provide arrangements to keep the current constant therein. The regulation of lamp current within a relatively narrow range is important in order to obtain reasonable lamp life and steady illumination. In resonant constant voltage to constant current transformation circuit means, such as the arrangement known as a monocyclic square, if the potential supplied thereto is constant, the current will be substantially constant, but if the potential varies, there will be a variation in load current.

One of the objects of the invention is to provide a circuit arrangement for a resonant circuit or static regulator system in which constant current will be supplied to the load regardless of variations, within limits, of line voltage and other factors.

Another object of the invention is to provide a circuit arrangement for a static type regulator of the resonant constant voltage to constant current type, wherein changes in the load current are utilized to apply corrections to saturable electro-magnetic devices in the system so as to maintain a constant applied current to the load.

This application is a continuation-in-part of application Serial No. 339,141, filed February 26, 1953.

In one aspect of the invention, a source of alternating current is connected to a resonant constant voltage to constant current transformation circuit, the output of said circuit being connected to the load which, for example, may be a lighting load. The resonant circuit may be a monocyclic square or a T circuit as will be described hereafter. A current sensing transformer or device is connected in the load circuit for producing a signal proportional to or a function of the load current. This signal is fed to a means comparing and amplifying any deviation therefrom to produce an indication signal. The means for producing the indication signal may be electro-mechanical, electronic, a magnetic amplifier or other similar device. The signal from the sensing and amplifying means is applied to the direct current winding of a saturable electro-magnetic means. As one example, the saturable electro-magnetic means in the monocyclic square may be in the form of saturable reactors. In another form, the output transformer between the resonant circuit and the load circuit may be a saturable transformer. The saturable electro-magnetic devices concerned have at least a control and a gate or load winding associated with a common core.

These and other objects, features, and advantages of the invention will become apparent from the following description and drawings, which are merely exemplary.

In the drawings:

Fig. 1 diagrammatically shows one circuit arrangement of the invention.

Fig. 2 shows a set of curves illustrating the manner

2

in which adjustment of the saturable reactor control current of Fig. 1 will cause the regulator to maintain substantially constant output current irrespective of changes in the input voltage.

Fig. 3 is an alternative form of the signal producing device of Fig. 1.

Fig. 4 is a still further form of the signal arrangement suitable for use in the circuit illustrated in Fig. 1.

Fig. 5 is a still further modification of a signal producing arrangement.

Fig. 6 illustrates another form of a resonant constant voltage to constant current transformation circuit, together with a saturable transformer in place of control of saturable reactors in the monocyclic square of the previous figures.

Fig. 7 is a resonant constant voltage to constant current transformation circuit similar to that of Fig. 6, except that the reactors therein have saturable reactors in parallel thereto.

Fig. 8 is a still further circuit arrangement.

The arrangements involved are particularly concerned with supplying a constant load current to a load by a resonant constant voltage to constant current transformation circuit independent of load impedance. The resonant constant voltage to constant current transformation

circuit may be of the monocyclic square type wherein the input is connected to two sides of a bridge arrangement having capacitors in opposite legs of the bridge and reactors in the other legs. It is also applicable to a resonant constant voltage to constant current transformation circuit of the T type, as will be explained hereafter. The T type has two reactors in series with a capacitor corrector across the line and between said reactors.

In these arrangements of resonant circuits, if the line voltage changes, the load current from the regulator will change proportionately, such being very objectionable. Inasmuch as it is well known that line voltage will not stay constant and may change as much as 10% either way, there will be a constant change in load current. The supply frequency and the capacitance and reactances of the resonant constant voltage to constant current transformation device also may vary so that compensation therefor must be provided for efficient operation of the arrangement.

In one form of the invention, a monocyclic square is used which is tuned by resonating the reactance of the inductors and capacitors that are in the monocyclic square. Changing one or the other sets of elements alone from resonance, has been found to be an effective way to change current level over a limited range, for example, $\pm 10\%$ of the normal current. Change of $\pm 30\%$ in the reactance of the reactor from the resonance value is sufficient to compensate for a $\pm 10\%$ change in line voltage in order to maintain a constant load current.

In the form of the invention now being described, reactors in the monocyclic square can be of the saturable electro-magnetic type, the reactance thereof being varied by variation in a direct current control winding, such serving to regulate the load current. The direct current control can be operated by an arrangement which measures or senses the load current or produces a signal in proportion thereto, the signal being amplified and compared with a predetermined value to produce a corrective control current for the monocyclic square and saturable reactors. The latter will serve to restore the load current to its predetermined constant value. In this way, any change in the load current caused by line voltage or other variation will be detected and corrected.

In the example shown in Fig. 1, input transformer 1 may have a primary winding 2, secondary winding 3, and control winding 4. The monocyclic square A is connected to secondary winding 3 of input transformer

1. The monocyclic square A may comprise four arms, two of which include reactor circuits 6 and 7 and the other two of which include capacitors 8 and 9. Reactor circuits 6 and 7 each may comprise fixed reactors 11 and 14 connected in parallel with saturable adjustable reactors 10 and 15 respectively. A fixed reactor is illustrated in parallel with a saturable reactor in the two arms of the square. It also is possible and preferable that only saturable reactors be used in the reactor arms of the monocyclic square or T type circuit.

Saturable reactors 10 and 15 are controlled by direct current control windings 12 and 16. In the form illustrated, direct current is supplied from control power winding 4 on input transformer 1 through adjustable resistor 18 and the rectifier 17. Adjustable resistor 18 is varied in accordance with the position of contact arm 19 which in turn is actuated by armature 20 and solenoid 21, the adjustable resistor arrangement thus being an electromechanical device.

The monocyclic square A has its output terminals connect to primary winding 27 of output transformer 26. The secondary winding of output transformer 26 is connected to the power distribution or load circuit 29.

The power distribution circuit 29 may include a control transformer 22, the primary thereof being in series with the secondary winding 28 of output transformer 26. The secondary winding 31 of control transformer 22 supplies power to solenoid 21 of the electro-mechanical device through adjustable resistor 23. Solenoid 21 controls position of armature 20 for positioning control 19 on resistor 18. The magnetic circuit of the solenoid 21 may be designed so that control arm 19 will cover its complete range on resistor 18 for a 2% or less change in solenoid current. It is important that the solenoid be extremely sensitive because otherwise too great a departure from desired level would be required in load current and solenoid current in order to actuate the corrective action. Resistor 18 may be connected to a bridge type rectifier 17, the rectifier receiving power from winding 4 of the input transformer 1.

Control transformer 22 preferably has an air-gap in its core so that the primary current in winding 25 will be proportional to the secondary voltage across secondary winding 31. Resistor 23 is adjusted so that the direct current in windings 12 and 16 on saturable reactor 10 and 15 will set the reactance of the saturable reactors to cause the monocyclic square to deliver the desired load current to load circuit 29. As the input voltage, the frequency, or the capacitances or inductance parameters in the monocyclic square change, the load current in load circuit 29 would tend to change and thus through control transformer 22 move armature 20 to cause the direct current in saturable reactor windings 12 and 16 to change so as to correct load current in load circuit 29. It can be seen that change in load current will result in a change in the rectified current received from rectifier 17 by the control windings 12 and 16 of saturable reactors 10 and 15 so as to control operation of the monocyclic square.

As an example of the manner of operation of the arrangement of Fig. 1, Fig. 2 shows characteristic curves and compensation of the system. These curves show the manner in which adjustment of the saturable reactor control current in windings 12 and 16 will cause the resonant constant voltage to constant current transformation circuit to maintain constant output current regardless of changes in input line voltage. The curves are plotted with input voltage as abscissas and control current ohms and amperes as ordinates. The curves have been plotted to show the characteristics of a 6.6 amp., 220 volt saturable reactor controlled system having the control current adjusted to maintain constant output current.

The set of curves shown at A illustrates the relation-

ship between output load current and input line current, it being noted that the output load current is constant.

The set of curves at B show the capacitor current in the monocyclic square as compared to the total reactor current in the fixed reactors 11 and 14 and the saturable reactors 10 and 15.

The set of curves at D show the relationship of the saturable reactor control current in windings 12 and 16 in their relation to the saturable reactor current of the circuit.

Fig. 3 illustrates another form of the invention wherein a signal proportional to the load circuit is used in conjunction with a magnetic amplifier arrangement. Points B', B' can be connected to B, B of Fig. 1, replacing the load circuit and control current determining arrangement thereof, points C', C' being connected to the saturable electro-magnetic device control winding. Output transformer 35 has its secondary 36 connected to load circuit 37, said load circuit having a load 30 therein. The current sensing transformer 38 has its primary 39 connected in load circuit 37. The secondary 40 of the current sensing transformer 38 is connected through an adjustable resistor 41 to bridge rectifier 42. The rectifier output is connected to control winding 43 of the magnetic amplifier 44. The magnetic amplifier is shown conventionally with two windings 45, 46 and control winding 43 and a second control winding 44' together with rectifier elements 45'. Control winding 44' may be connected to a source of direct current 46' for setting up a reference voltage or bias on the magnetic amplifier 44. The magnetic amplifier 44 is connected to the bridge rectifier 47, the output of the rectifier 47 having leads indicated at C', C'. The leads C', C', for example, may be connected to points C, C of Fig. 1, which in turn are connected to the saturable reactor control windings 12 and 16 of the resonant constant voltage to constant current transformation circuit means thereof. A source of alternating current 48 is connected to the magnetic amplifier and rectifier 47. Thus, a change in load current in the load circuit 37 of Fig. 3 will provide a compared and amplified deviation of the signal from the current sensing transformer to produce an indication signal which will adjust the saturable reactors of the resonant constant voltage to constant current transformation circuit means. The control windings of the magnetic amplifier are connected so that an increase in load current will reduce the saturating current delivered to the saturable reactors in the regulator means. The current sensing transformer also may have a tapped secondary in place of the variable resistor for setting load current.

Another form of control power supply in place of using power from the input transformer is seen in Fig. 4 wherein terminals B', B' leading to the primary of output transformer 50 may be connected to B, B of Fig. 1 to replace the load sensing portion. The secondary 51 of output transformer 50 is connected to load circuit 52 having load 53 therein. Current sensing transformer 54 has its primary 55 in the load circuit 52, the secondary 56 being connected to solenoid 57. Solenoid 57 controls the wiper or contactor 58 of the resistor 59, the contactor being connected with lead 60 similar to Fig. 1. Control power transformer 61 has its primary 62 in the load circuit 52 and a secondary 63 connected to rectifier 64 through the resistor 59. Thus, resistor 59 and solenoid 57 are parts of the electro-mechanical regulator arrangement. The output of the rectifier 64 can have terminals C', C' connected to C, C of Fig. 1 so as to furnish control current to the control windings 12 and 16 of the saturable reactors 10 and 15. In this form, control power is taken from the regulated load circuit. If the control power is relatively small compared to the load power, for example, 1%, this form is very economical in operation.

Fig. 5 illustrates a further form of the invention in which an electronic tube arrangement is employed to supply the control direct current to the control winding

of the saturable reactor. Terminals B', B' thereof may be connected to B, B or output of the monocyclic square of Fig. 1. Output transformer 64 has its secondary 66 connected to load circuit 67 having load 68 therein. The current sensing transformer 69 has its primary 70 in load circuit 67, the secondary 71 being connected to rectifier 72. The output of the rectifier has one side connected to grid 73 of the electronic tube 74. A variable resistor 75 is connected across the grid and the lead 76 from the other side of the rectifier to the plate circuit D.C. supply 77. Cathode 78 of tube 74 is connected to lead 76 through a reference voltage source 79. Leads C', C may be connected to points C, C of Fig. 1 to furnish the control D.C. for the control windings of the saturable reactor.

In addition to the monocyclic square arrangement described in Figure 1, a T type resonant constant voltage to constant current transformer circuit such as illustrated in Figure 6 can be used in place thereof.

In the embodiment shown in Figure 6, input power can be supplied to terminals 90 by an input transformer such as 1 of Fig. 1 to the T type resonant constant voltage to constant current transformation circuit D. This circuit comprises reactors 91 and 92 in series with primary 93 of the output transformer 94. A capacitor 95 is connected at one point between reactors 91 and 92 and at its other side between primary 93 and terminal 90. In place of the usual output transformer as illustrated in Figure 1, a saturable transformer 94 is illustrated having a D.C. control winding 96. A saturable transformer arrangement is described in more detail hereafter in conjunction with Fig. 8.

The secondary 97 of the output transformer 94 can be connected to the load circuit at points E, E of Figure 1. A current sensing transformer in the load circuit such as shown in Figure 1 then can be used to supply control voltage at C, C of Figure 1 to the D.C. control winding 96 at C', C' of Figure 6.

Another form of resonant constant voltage to constant current transformer which can be used in place of the monocyclic square A in Figure 1, and the other forms, is seen in Figure 7. In this embodiment, input power supply is connected at leads 100 to the T type resonant constant voltage to constant current transformer arrangement F having fixed reactors 101 and 102 with saturable reactors 103 and 104 in parallel thereto. The saturable reactors have D.C. control windings 105 and 106. The load circuit or output transformers of the prior circuits may be connected at terminals 107. The current sensing transformer arrangement of the load circuit then may operate through its control arrangements to produce, for example, control D.C. at C, C of Figure 1 which can be connected to each of the control windings 105 and 106 of Figure 7.

The circuits of Figures 6 and 7 thus will produce a controlled load current from A.C. supply systems.

As another example of a complete circuit employing a saturable transformer, reference may be made to Figure 8. The monocyclic square G has reactors 108, 109 in two arms thereof and capacitors 110 and 111 in the other arms thereof, said monocyclic square being supplied by a source of alternating current 112. The output of the monocyclic square G is connected to saturable transformer 113, said saturable transformer having primary windings 114 and 115 connected to the opposite corners of the monocyclic square. Secondaries 116 and 117 are connected in load circuit 118 having the load diagrammatically illustrated at 119. The D.C. control winding 120 is inductively related to the windings of the saturable transformer 113. Current sensing transformer 121 has its primary 122 in the load circuit, the secondary 123 being connected to solenoid 124. Solenoid 124 may operate contact fingers 125 in devices such as the type shown as "Regohm," having fingers which are connected to the resistor 125' thereof.

Power for the control current may be supplied from the supply source 112 through the control transformer 127. Bridge rectifier 128 supplies control D.C. to the control winding 120 in accordance with the current flowing in the load circuit 118.

Merely by way of example, the saturable output transformer 113 can be one built on a 3 legged core with the control winding on the middle leg and the alternating current winding on the outer two legs. One primary and one secondary alternating current coil can be placed on each outer leg, the two primary coils being connected in series and the two secondary coils connected in series in such a manner that there will be no induced line frequency voltage in the control windings.

It should be apparent that variations may be made in the details of construction and arrangement without departing from the spirit of the invention except as defined in the appended claims.

I claim:

- 20 1. In a system for compensating for variations in an alternating current supply system with respect to a power distribution load circuit, the combination including a resonant constant voltage to constant current transformation circuit means for feeding said load circuit, signal means connected to said load circuit producing a signal proportional to the load current in said load circuit, means comparing and amplifying deviation of said signal from a predetermined value to produce an indication signal, saturable reactor means in said resonant circuit means, and means connecting the control winding means of said saturable reactor with said means comparing and amplifying said signal.
- 25 2. In a system for compensating for variations in an alternating current supply system with respect to a power distribution load circuit, the combination including a monocyclic square having four interconnected arms with capacitors in two opposite arms and reactors in the other two opposite arms, input supply means for said square, output load circuit connections with said square, signal means connected to said load circuit producing a signal proportional to the load current in said load circuit, means comparing and amplifying deviation of said signal from a predetermined value to produce an indication signal, control windings associated with the arms having reactors in said square, and means supplying control current to said control windings in accordance with said indication signal for compensating through said monocyclic square for variations in said power supply system.
- 30 3. In a system for compensating for variations in a power supply system with respect to a power distribution circuit comprising an alternating current power supply system, a power transformer including a primary winding and a pair of secondary windings, a monocyclic square including four interconnected arms in which two of said arms include reactor circuits and the two opposite arms include capacitors, input terminals for said monocyclic square connected with one of said secondary windings, output terminals for said monocyclic square connected to an output transformer, a power distribution circuit connected with said last-mentioned output transformer, a separate transformer included in said power distribution circuit, a regulating circuit controlled by said last-mentioned separate transformer, means for supplying energy to said regulating circuit from one of the secondary windings on the first-mentioned transformer and control windings associated with the first-mentioned arms of said monocyclic square and electrically controlled from said regulating circuit for compensating through said monocyclic square for variations in said power supply system.
- 35 4. In a system for compensating for variations in a power supply system with respect to a power distribution circuit, as set forth in claim 3, in which the reactor circuits in the said first-mentioned arms of said monocyclic square include fixed reactors and saturable adjustable re-

actors, respectively, connected in parallel with said fixed reactors and in which said control windings are inductively associated with said saturable adjustable reactors and receive control current from said regulator circuit.

5. In a system for compensating for variations in a power supply system with respect to a power distribution circuit, as set forth in claim 3, in which said regulating circuit receives power from one of the secondary windings of said first-mentioned transformer, said regulating circuit including an adjustable resistor and a rectifier system therein and means controlled from the separate transformer in the power distribution circuit for controlling the effective value of said resistor and control windings coupled with the first-mentioned arms of said monocyclic square and connected with the output of said rectifier for controlling the operation of said monocyclic square in accordance with variations incident upon said power distribution circuit and/or said power supply system.

6. In a system for compensating for variations in a power supply system with respect to a power distribution circuit, as set forth in claim 3, in which said regulating circuit includes a variable control element connected with said separate transformer, said means including a resistance and a rectifier, means controlled by said variable control element for controlling the effective value of said resistance for correspondingly controlling the current impressed upon said rectifier and circuit connections from the output of said rectifier to said control windings in said monocyclic square for controlling the operation of said monocyclic square according to variations existent in said power distribution circuit.

10

7. In a system for compensating for variations in a power supply system with respect to a power distribution circuit, as set forth in claim 3, in which the regulating circuit includes a solenoid winding, an armature controlled by said solenoid winding, a switch arm controlled by said armature, a resistance over which said switch arm operates, a rectifier having its input circuit included in series with said resistance and connected with one of the secondary windings of said first-mentioned transformer, and control windings inductively associated with the reactor circuits of the first-mentioned arms of said monocyclic square and electrically connected in series with the output of said rectifier whereby the operation of said monocyclic square is compensatingly controlled through the operation of said regulating circuit.

15 8. The system set forth in claim 1 wherein the resonant constant voltage to constant current transformation circuit means comprises a pair of saturable reactors connected in series with the input and output of the transformation circuit means and a capacitor is connected across said input between said reactors.
